UNITED STATES PATENT OFFICE.

HENRY MOYES, OF ELTHAM, NEW ZEALAND.

HAT-FASTENER.

1,308,296.

Specification of Letters Patent.

Patented July 1, 1919.

Application filed August 16, 1918. Serial No. 250,129.

To all whom it may concern:

Be it known that I, HENRY MOYES, a citizen of the Dominion of New Zealand, and residing at London Street, Eltham, in the 5 Provincial District of Taranaki, in the Dominion of New Zealand, have invented certain new and useful Improvements in Hat-Fasteners, of which the following is a specification.

10 This invention relates to means for securing a hat upon a woman's head, and provides a fastener whereby a hat can be securely retained on the head without making unsightly holes in the sides of the hat as occurs when the usual pin is employed.

The invention comprises parallel pins passing through bosses or sockets fixed to opposite sides of a hat. Each pin has a fixed socket, in which the other pin is slidable, 20 and crinkled prongs fixed to the socket project downward and inward. The ends of the pins outside the hat are provided with ornamental knobs.

The friction of the sockets on the pins 25 may be increased by means of springs pressing on the pins.

The prongs are made to engage the hair of the wearer by pulling out or pushing in the ornamental knobs, according as the sockets are fixed at the inner ends of the pins or 30 near the ornamental knob.

The invention may be conveniently and advantageously carried into practice as shown in the accompanying drawing, wherein:

Figure 1, is a side elevation,

Fig. 2, a plan of the fastener with the sockets fixed at the inner end of the pins,

Fig. 3, is a side elevation of the fastener 40 in position for securing a hat,

Fig. 4, is a plan of the fastener with the sockets fixed near the ornamental knob,

Fig. 5, is a perspective view of the fastener provided with friction springs, and

Fig. 6, is a sectional elevation of a socket 45 fitted with a friction spring.

Referring more particularly to Figs. 1, 2, and 3, the pins 1 and 2 are arranged parallel to each other and with their points reversed 50 in direction. Duplex sleeve-like sockets 3 and 4 are fixed to the pins 1 and 2 respec-

tively. The pin 1 is slidable in the socket 4, and the pin 2 is slidable in the socket 3. Prongs 5 are fixed to the socket 3, and prongs 6 are fixed to the socket 4. The said 55 prongs are formed of flexible wire and are crinkled to increase their hold when inserted in the hair of the wearer. In addition, these prongs are bent downwardly and inwardly and are positioned upon opposite 60 sides of the sockets so as to readily enter the hair.

Wearing members such as plates, bosses or sockets 7 and 8 are fixed to the sides 9 of the hat, and either on the inner side thereof as shown in Figs. 1, 2 and 3, or on the outer side of the same as shown in Fig. 4. If the wearing member is fixed on the outer side of the hat, the same may be made with an ornamental design or covered with any suitable material.

The pins 1 and 2 are provided with ornamental knobs 10 and 11 respectively outside the hat.

In use, the hat is placed on the head of 75 the wearer with the sockets and prongs in the position shown in Figs. 1 and 2. The knobs 10 and 11 are then pulled outwardly to draw the prongs into the hair of the wearer as shown in Fig. 3, and in dotted 80 lines in Fig. 2. During this operation the socket 3 slides on the pin 2, and the socket 4 slides on the pin 1, each pin forming a guide for the socket fixed to the other pin.

Referring now more particularly to Fig. 85 4 where the sockets are shown fixed near to the knobs, the said knobs are pushed inward to push the prongs into the hair.

Referring more particularly to Figs. 5 and 6 the sockets are made with slots 12, and 90 springs 13 fixed by rivets 14 to the sockets press upon the pins 1 and 2. The friction of the springs assists the friction of the sockets in keeping the prongs in engagement with the hair.

What I desire to obtain and secure by Letters Patent of the United States is:—

A hat fastener comprising parallel pins arranged through opposite sides of a hat, a duplex sleeve-like socket fixed to each pin 100 and through which the other pin is slidable, the portions of the sockets through which

the pins are slidable being provided with slots, leaf springs fixed to the sockets near one end of the slots therein and arranged in the slots for frictional engagement with the adjacent pins, and crinkled flexible prongs carried by the pins and bent downwardly and inwardly and arranged on opposite sides of the sockets.

In testimony whereof I have signed my name to this specification in the presence of 10 two witnesses.

HENRY MOYES.
